(57) **CLAIM**

We claim the ornamental design for industrial robot, as shown and described.

DESCRIPTION

FIG. 1 is a front view of an industrial robot;

FIG. 2 is a rear view thereof;

FIG. 3 is a right side view thereof;

FIG. 4 is a left side view thereof;

FIG. 5 is a top view thereof;

FIG. 6 is a left perspective view thereof; and,

FIG. 7 is a right perspective view thereof.
